(57) **CLAIM**

The ornamental design for an election voting network controller display screen with graphical user interface, as shown and described.

DESCRIPTION

FIG. 1 is a front view of an election voting network controller display screen with graphical user interface.

FIG. 2 is a front view of an embodiment of the design of FIG. 1; and,

FIG. 3 is a front view of an embodiment of the design of FIG. 1.

The broken line showing of an election voting network controller display screen with graphical user interface is included for the purpose of illustrating portions of the article and forms no part of the claimed design.

1 Claim, 2 Drawing Sheets
